ADJUSTING DEVICE FOR ROTARY PISTON
PUMPS

Prosper L'Orange, Stuttgart-Feuerbach, Germany; Rudolf L'Orange executor of the estate of said Prosper L'Orange, deceased

Application June 19, 1939, Serial No. 279,977
In Germany June 20, 1938

6 Claims. (Cl. 103—41)

This invention relates to means for angularly adjusting the position of the piston relatively to the cylinder in which it works of rotary piston pumps for the purpose of adjusting the output of the pump for a given number of reciprocations of the piston per unit of time in the operation of the pump.

It is known that the angular adjustment of the piston in such pumps has to be effected with a high degree of accuracy and it is very desirable that the measure of the adjustment that has been effected in the one direction or the other shall be definite and known, particularly when an adjustment of a very small magnitude is made. Heretofore this has not been possible with the forms of adjusting means that have been used, which have generally involved the use of parts which, to effect an adjustment, have required to be unclamped and then reclamped again in their adjusted relative positions. As will be understood, an arrangement of this character does not enable a fine adjustment of a definitely known magnitude to be obtained, at any rate with ease, and in addition the parts that are clamped together may tend to work loose with consequent disturbance of the adjustment that has been effected. In addition, the arrangements that have been used have generally been such as to necessitate a dismantling of certain parts of the pump to effect the adjustment, which again is a serious disadvantage from the practical point of view.

The object of the present invention is to provide an improved construction in these respects, that is, an improved construction in virtue of which it will be possible to effect a very fine and accurate adjustment of a definite and known magnitude and without the necessity of dismantling any of the parts of the pump, the arrangement being such, moreover, as will enable the adjustment to be made with great ease and rapidity.

According to the invention, an adjusting device for a rotary piston pump in which regulation of the output of the pump is effected by an angular adjustment of the position of the piston with respect to the cylinder in which it works, comprises a part which is in fixed relationship in the rotational sense with the piston, a second part which is coaxial with the first part and which is angularly movable about the axis thereof to effect the angular adjustment of the piston and an intervening coupling ring interposed between the first part and the second part and having toothed engagement with each of

the parts so as positively to couple them together for angular adjustment as one about the said axis of the parts, which toothed engagement is of such a character as to enable an angular adjustment to be effected both of the ring relatively to the first part and also of the ring relatively to the second part with the magnitude of the adjustment per tooth step thereof slightly different in the one case from in the other so that by conjoint adjustment of the ring with adjustment of the relative positions of the parts on either side of it a very fine and definite adjustment of the two parts relatively to one another may be effected, provision being made for relative axial movement of the parts to enable the adjustment of the ring to be effected.

According to a preferred form of the invention, the arrangement is one in which the coupling ring has at one end a number of equally spaced recesses, slots, notches or the like, all hereinafter referred to as graduations and at the opposite end a different number of equally spaced recesses, slots, notches or the like, all hereinafter referred to also as graduations, and the two parts on either side of the ring which are coupled together thereby carry each a projection adapted to engage in any of the graduations of the corresponding set thereof, the set of graduations at one end of the ring being arranged to co-operate with the projection on the part adjacent that end thereof and the set at the other end of the ring being arranged to co-operate with the projection on the other part.

The number of graduations at the end of the ring is different from that at the other end thereof by only a small amount, for example one, in which event it will be the case that with a complete rotation of the ring through 360°, an adjustment equal only to the graduation angle is obtained, since the effect of a rotation of the ring is that of a movement equal to the graduation angle, for example, the upper graduation angle divided by the number of the lower graduations.

It is easily possible, for example by an adjustment of the ring by one graduation tooth towards the right, to obtain an alteration of $+\frac{1}{16}$ mm., and with an adjustment towards the left an alteration of $-\frac{1}{16}$ mm., and these numerical values may be stamped on the ring.

The said second part above-mentioned of the adjusting means, that is, the part which is angularly movable about the common axis of the two parts to effect the angular adjustment of the piston, may be slidably and rotatably mount-

ed on a sleeve coaxial with the parts and connected to the said first part, that is, the part which is in fixed relationship in the rotational sense with the piston of the pump. In this 5 event, a convenient arrangement is one in which the said second part is normally urged into operative engagement with the coupling ring and the latter with the first part, by a compression spring interposed between the second part and 10 an abutment carried upon the sleeve.

The said second part of the adjusting means may be, for example, a toothed wheel, toothed segment or regulating lever, forming part of a 15 means for automatically regulating the output of the pump.

The invention will now be further described with reference to the accompanying drawing:

Figure 1 of which is generally speaking an external view of the relevant parts of an adjusting 20 means in accordance with the invention, and

Figure 2 is a central longitudinal section through the said parts appearing in Figure 1 taken on the section line 2—2 thereof.

Referring to the drawing, the said relevant 25 parts therein shown comprise an annular member A constituting the part of the adjusting means hereinbefore referred to as the "first" part. The member A carries in integral connection with it a sleeve A₁ and freely revoluble thereon is a regulating toothed wheel B. This 30 wheel constitutes the part of the adjusting means hereinbefore referred to as the "second" part. A projection C on the underside of the regulating toothed wheel B engages in one of a 35 set of graduations in the form of slots at one end of an intermediate coupling ring E. A stop, in the form of a dowel pin F, mounted on the member A, engages in one of a second set of graduations, also in the form of slots, at the 40 other end of the coupling ring E. The regulating toothed wheel B is forced on to the ring E and the ring E is caused to bear against the member A by means of a compression spring G, the upper end of which abuts against a collar H 45 secured to the upper end of the sleeve A₁ by means of a spring ring I. In accordance with the description of the invention earlier given herein, the number of slots at the lower end of the ring E is greater by one than the number 50 at the upper end and it will be understood that the annular member A is in fixed relationship in the rotational sense with the piston of the pump, which as usual occupies a position centrally 55 within the adjusting means comprising the foregoing parts.

What I claim as my invention and desire to secure by Letters Patent of the United States is:

1. An adjusting device for a rotary piston 60 pump in which regulation of the output of the pump is effected by an angular adjustment of the position of the piston with respect to the cylinder in which it works, which comprises a part which is in fixed relationship in the rotational sense with the piston, a second part which 65 is coaxial with the first part and which is angularly movable about the axis thereof to effect the angular adjustment of the piston and an intervening coupling ring interposed between the first part and the second part and having 70 toothed engagement with each of the parts so as positively to couple them together for angular adjustment as one about the said axis of the parts, which toothed engagement is of such a character as to enable an angular adjustment 75 to be effected both of the ring relatively to the

first part and also of the ring relatively to the second part with the magnitude of the adjustment per tooth step thereof slightly different in the one case from in the other so that by conjoint adjustment of the ring with adjustment 5 of the relative positions of the parts on either side of it a very fine and definite adjustment of the two parts relatively to one another may be effected, provision being made for relative axial movement of the parts to enable the adjustment 10 of the ring to be effected.

2. An adjusting device for a rotary piston pump in which regulation of the output of the pump is effected by an angular adjustment of the position of the piston with respect to the cylinder in which it works, which comprises a part which is in fixed relationship in the rotational sense with the piston, a second part which is coaxial with the first part and which is angularly movable about the axis thereof to effect the angular adjustment of the piston, a sleeve coaxial with the first part and connected thereto, the second part being mounted on the sleeve so as to be freely revoluble and axially slidable thereon, and an intervening coupling ring interposed between the first part and the second part and having toothed engagement with each of the parts so as positively to couple them together for angular adjustment as one about the said axis of the parts, which toothed engagement is of such a character as to enable an angular adjustment to be effected both of the ring relatively to the first part and also of the ring relatively to the second part with the magnitude of the adjustment per tooth step thereof slightly 30 different in the one case from in the other so that by conjoint adjustment of the ring with adjustment 35 of the relative positions of the parts on either side of it a very fine and definite adjustment of the two parts relatively to one another may be effected.

3. An adjusting device for a rotary piston pump in which regulation of the output of the pump is effected by an angular adjustment of the position of the piston with respect to the cylinder in which it works, which comprises a part which is in fixed relationship in the rotational sense with the piston, a second part which is coaxial with the first part and which is angularly movable about the axis thereof to effect the angular adjustment of the piston, a sleeve coaxial with the first part and connected thereto, the second part being mounted on the sleeve so as to be freely revoluble and axially slidable thereon, an intervening coupling ring interposed 50 between the first part and the second part and having toothed engagement with each of the parts so as positively to couple them together for angular adjustment as one about the said axis of the parts, which toothed engagement is of such a character as to enable an angular adjustment to be effected both of the ring relatively to the first part and also of the ring relatively to the second part with the magnitude of the adjustment per tooth step thereof slightly different 60 in the one case from in the other so that by conjoint adjustment of the ring with adjustment of the relative positions of the parts on either side of it a very fine and definite adjustment of the two parts relatively to one another may be 65 effected, and a compression spring interposed between the second part and an abutment on the sleeve and operative normally to maintain the parts and the ring in operative engagement.

4. An adjusting device for a rotary piston 75

5 pump in which regulation of the output of the
pump is effected by an angular adjustment of
the position of the piston with respect to the
cylinder in which it works, which comprises a
part which is in fixed relationship in the rota-
tional sense with the piston, a second part which
is coaxial with the first part and which is an-
gularly movable about the axis thereof to effect
the angular adjustment of the piston and an
10 intervening coupling ring interposed between
the first part and the second part and formed at
one end with a set of equally spaced tooth-enga-
gement graduations arranged to be engaged one at
a time by a projection on the first part
15 and at the other end with a second set of equally
spaced tooth-engagement graduations of a dif-
ferent number from the number in the first set
and arranged to be engaged one at a time by a
projection on the second part, whereby by con-
20 joint adjustment of the ring with adjustment
of the relative positions of the two parts on
either side of it, a very fine and definite adjust-
ment of the two parts relatively to one another
may be effected, provision being made for rela-
25 tive axial movement of the parts to enable the
adjustment of the ring to be effected.

5. An adjusting device for a rotary piston
pump in which regulation of the output of the
pump is effected by an angular adjustment of
the position of the piston with respect to the
cylinder in which it works, which comprises a
30 part which is in fixed relationship in the rota-
tional sense with the piston, a second part which
is coaxial with the first part and which is an-
gularly movable about the axis thereof to effect
the angular adjustment of the piston, a sleeve
35 coaxial with the first part and connected there-
to, the second part being mounted on the sleeve
so as to be freely revoluble and axially slid-
able thereon, and an intervening coupling ring inter-
posed between the first part and the second part
40 and formed at one end with a set of equally
spaced tooth-engagement graduations arranged
to be engaged one at a time by a projection on

the first part and at the other end with a second
set of equally spaced tooth-engagement gradu-
ations of a different number from the number in
the first set and arranged to be engaged one at
a time by a projection on the second part, where-
5 by by conjoint adjustment of the ring with adjust-
ment of the relative positions of the two parts
on either side of it, a very fine and definite ad-
justment of the two parts relatively to one an-
other may be effected.

6. An adjusting device for a rotary piston
pump in which regulation of the output of the
pump is effected by an angular adjustment of
the position of the piston with respect to the
cylinder in which it works, which comprises a
15 part which is in fixed relationship in the rota-
tional sense with the piston, a second part which
is coaxial with the first part and which is an-
gularly movable about the axis thereof to effect
the angular adjustment of the piston, a sleeve 20
coaxial with the first part and connected there-
to, the second part being mounted on the sleeve
so as to be freely revoluble and axially slid-
able thereon, an intervening coupling ring interposed
25 between the first part and the second part and
formed at one end with a set of equally spaced
tooth-engagement graduations arranged to be
engaged one at a time by a projection on the
first part and at the other end with a second set
30 of equally spaced tooth-engagement graduations
of a different number from the number in the
first set and arranged to be engaged one at a
time by a projection on the second part, whereby
by conjoint adjustment of the ring with ad-
35 justment of the relative positions of the two
parts on either side of it, a very fine and definite
adjustment of the two parts relatively to one
another may be effected, and a compression
spring interposed between the second part and
40 an abutment on the sleeve and operative nor-
mally to maintain the parts and the ring in op-
erative engagement.

PROSPER L'ORANGE.
